UNITED STATES PATENT OFFICE.

MORRIS SCHLEPP, OF NEW YORK, N. Y.

DESIGN FOR A GLOBE-HOLDING CEILING FIXTURE.

Application filed July 11, 1928. Serial No. 27,446. Term of patent 7 years.

To all whom it may concern:

Be it known that I, MORRIS SCHLEPP, a citizen of the United States, and a resident of the city of New York, borough of Manhattan, in the county of New York and State of New York, have invented a new, original, and ornamental Design for a Globe-Holding Ceiling Fixture, of which the following is a specification.

In the accompanying drawings—

Figure 1 is a bottom plan view of a globe

holding ceiling fixture showing my new design.

Figure 2 is a view in side elevation.

I claim:

The ornamental design for a globe holding ceiling fixture, as shown.

Signed at New York, in the county of New York and State of New York, this 10th day of July, A. D. 1928.

MORRIS SCHLEPP.
